UNITED STATES PATENT OFFICE.

JOHN A. KANE, OF PATERSON, NEW JERSEY.

STATION-INDICATOR.

SPECIFICATION forming part of Letters Patent No. 462,138, dated October 27, 1891.

Application filed February 14, 1891. Serial No. 381,407. (No model.)

To all whom it may concern:

Be it known that I, JOHN A. KANE, of Paterson, in the county of Passaic and State of New Jersey, have invented a new and Improved 5 Station-Indicator, of which the following is a full, clear, and exact description.

The invention relates to indicators for use on railway-cars for indicating the successive stations along the road, the object being to 10 provide an efficient and durable indicator of this character.

The invention consists in the construction and arrangement of parts, all as hereinafter specifically described, and defined in the 15 claims.

Reference is to be had to the accompanying drawings, forming a part of this specification, in which similar letters of reference indicate corresponding parts in all the figures.

20 Figure 1 is a front elevation of a station-indicator constructed in accordance with my invention. Fig. 2 is a similar view with the front or door of the casing opened and partly broken away. Fig. 3 is an end view. Fig. 4 25 is a broken view of the inside of the hinged door or front of the casing, showing the latch devices therefor. Fig. 5 is a broken plan view thereof. Fig. 6 is a transverse sectional elevation on line 6 6, Fig. 2. Fig. 7 is a like 30 view on the line 7 7, Fig. 2, parts being omitted. Fig. 8 is a like view on line 8 8, Fig. 2, parts being omitted. Fig. 9 is an end elevation of the main operating mechanism or station-tripping devices for automatically operating the indicator. Fig. 10 is a partly sectional side view of the trip-arm support, and Fig. 11 is a sectional plan view on line 11 11 of Fig. 9.

35 The casing A of the indicator is suitably 40 fitted or formed in a railway-car transversely of the latter, and is formed with a hinged front or door A', having on its inner side latch devices B, which are operated from the knob or handle B', as hereinafter explained.

45 In the case A the main shaft C of the indicator is suitably journaled, the shaft being extended at each end beyond the case A and provided with arms c, which extend radially therefrom and are adapted to be tripped by 50 the arm D, Fig. 9, of the station-tripping devices, with which each station along the road is provided, and by means of which a partial

rotation is given to the shaft C. On the shaft C the main roller or drum E is fitted to rotate with said shaft, to which drum E is secured 55 one end of the web F, of fabric or any suitable material, bearing the names of the several stations, the rotation of the drum in response to the movements of its shaft C serving to successively display the names of the several stations at the opening a in the front A' of the case A. Parallel with the drum E and beneath the same a winding-roller G and a guide-roller H are journaled, respectively, in brackets or standards g g' and h h, the web F being 60 secured to the winding-roller G, and passing forward over the guide-roller H to the drum E. The winding-roller G carries a pinion g', which meshes with a gear-wheel I, the shaft I' of which is journaled in the brackets g g, and 65 to the shaft I' one end of a coiled spring I' is secured, its other end being secured to one of said brackets g or to other suitable fixed supports. Thus as the drum E is rotated in the direction of the arrow shown in Figs. 6 and 7 70 the spring I' will be wound, and when the drum is rotated in the inverse direction of the arrow the spring tends to take up the slack, winding the web F on the roller G. At the ends of the drum E the same is provided 75 with squared hubs E', formed, preferably, with rounded projections or beads e at the angles, and against one face of each of said hubs a spring-acted controlling-head J bears. The heads J are each formed with two arms 80 j, which are mounted in the brackets j' j', secured to and projecting from the opposite faces of the back of the case A, said arms passing through apertures in said brackets and through apertures a' in the case. Around 85 the arms j spiral springs j' are wound and normally act to press the heads J against the hubs E' of the drum, and on the outer ends of the arms j buffer-blocks j' are adjustably secured, as by washers j'', held by pins, which 90 enter suitable apertures in the said arms. Within the brackets j' yokes j'', formed similarly to said brackets, are arranged, the cross-bars j''' of said yokes being operated for the passage therethrough of the arm j. The 95 springs j' thus abut at their outer ends against the cross-bars j'''. The yokes j'' are supported adjustably at their inner ends from the case A by bolts j'', and by adjusting said bolts the

said yokes may be moved to give more or less tension to the springs j^3 . The controlling-heads J so arranged serve to arrest the rotary movement of the drum E , limiting its 5 movement to a quarter-revolution.

The arm D of the automatic tripping mechanism at each station is secured to a square shaft M , which is rounded where it rests in its supporting-brackets M' , and is yieldingly 10 maintained in position to permit it to rock slightly by means of a spring, which is coiled into a loop m' , and its ends m^2 are extended in opposite directions and are secured to slices m , which are held on plates m^3 , secured 15 to the vertical screw-rods m^4 , which pass through apertures in the bottoms of the hangers M^2 , wing-nuts m^5 or other suitable nuts serving to hold the rods in the adjusted position. By moving the ends of the spring up 20 or down the desired tension is obtained.

In addition to the main or station tripping devices, an auxiliary hand-operated actuating device is provided for moving the drum E and the web F in either direction. The auxiliary device is best shown in Fig. 8, and comprises a vertically-disposed lever K , which is fulcrumed at k on the case A , and hooks K' , pivoted at about their centers in the forked upper end of said lever, the hooks being oppositely arranged. The hooked ends k' of the hooks K' are connected with springs k^2 , having a tendency to normally maintain said hooks out of engagement with the rounded projections e of the square hub E' , and to the 35 opposite ends of said hooks chains or cords K^2 are secured and hang freely below the case A in proximity to the lever K . Thus by pulling on either of the chains K^2 the hooked end of the corresponding hook K' is thrown 40 upward into engagement with the adjacent projection e , as shown in dotted lines in Fig. 8, whereby as the lever K is thrown on its fulcrum the hook K will give a partial rotation to the drum E . If the opposite hook be 45 thrown up and the lever K thrown in the opposite direction, a corresponding movement will be given the drum E . The auxiliary devices thus serve to adjust or actuate the drum and web as desired when it is not required 50 to display the stations in the regular succession.

The names of the stations, such as "Grand," are produced on the web F , and the characters and letters "St. Next" are permanently 55 produced on the case, so that when a name on the web is presented at the opening the announcement will be read in connection with the permanent characters, thus: "Grand St. Next."

60 In connection with the indicator an alarm mechanism is employed to attract the attention of the passengers to the station announced, the alarm being as follows: In the periphery of the drum E , at one end, recesses 65 e' are formed and so located that when the drum is at a standstill one of such recesses will be opposite an arm l , Fig. 6, carried by

hinged block L , which carries on its lower face a contact-plate l' , which is arranged in connection with a second contact-plate l^2 , such 7 second contact-plate being held to the opposed block L' , both blocks $L L'$ being normally held apart by a spring l^3 . From the contact-plates $l' l^2$ the line-wires l^4 lead to a battery L^2 and electric bell L^3 , the bell in the 75 present instance being carried by the hinged front Δ' of the casing. The arrangement of the signal is such that as the drum E is rotated the spring-arm l is forced from the recess e and acts to throw the hinged block L 80 downward and complete the electric circuit by causing the plates $l' l^2$ to contact, the circuit being maintained closed until the next succeeding opening is brought opposite the spring-arm l , permitting the blocks $L L'$ to 85 separate and break the circuit.

The latch devices B for the door A' , which are best shown in Figs. 4 and 5, are as follows: At each end of the said door, on the inside, latches B^2 in the form of bell-cranks are 90 pivoted and engage by one arm b with catches b^2 on the case A , the other arm b' of each catch serving as a stop to limit the movement of said latches. To the arms b are connected wires b^3 , which extend to opposite ends of the lever 95 b^4 , which is secured to the spring-acted spindle b^5 of the knob B' , whereby as the said knob is turned both latches B^2 will be simultaneously disengaged from their respective catches b^2 and permit the hinged door to be 100 opened.

By yieldingly mounting the trip-arms D the necessary resistance is given to the arms c of shaft C , while at the same time all injurious shocks are prevented, the spring-acted 105 controlling-heads J coacting with the yield-ing trips D to reduce the shock.

By providing an auxiliary operating mech-anism in addition to the main automatic trips the drum may be rotated at will in either di-rection, as may be necessary when the train 110 is not traveling the whole length of the road, and the stations, therefore, not required to be announced in the regular succession.

Having thus described my invention, what I 115 claim as new, and desire to secure by Letters Patent, is—

1. In a station-indicator, the operating-arm provided with a horizontal rock-shaft M , having bearings $M' M'$, in combination with the 120 springs m' , coiled oppositely at their inner ends around the said shaft, hangers at opposite sides of the shaft provided with verti-cally-adjustable plates or seats, to which are secured the oppositely-projecting outer ends 125 m^2 of the said springs, substantially as set forth.

2. The combination, with the bearings $M' M'$, and the rock-shaft M , mounted therein and having an indicator-operating arm, of the hangers $M^2 M^2$ at opposite sides of the shaft, screws m^4 , extending up through the lower ends of the hangers and provided with adjusting-nuts, seats in the hangers connected 130

to the upper ends of said screws, and the springs m' , coiled around the said shaft in opposite directions, with their ends m^2 connected to said seats or plates, substantially as set forth.

3. In a station-indicator, the combination, with the horizontal rocking shaft having an indicator-operating arm projecting therefrom, of a spring coiled at its inner end about the shaft and projecting outward at its opposite end from the shaft, and an adjusting mechanism to one side of the shaft, and with which the outwardly-projecting end of the spring is connected, whereby the tension of the spring

15 may be varied, substantially as set forth.

4. In an indicator, the combination, with the main drum having a polygonal head provided with projections, of the operating-lever K , having two oppositely-projecting hooks K' , 20 pivoted between their ends to its upper end and provided with springs k^2 , normally holding them out of engagement with said head, and a chain or cord K^2 , secured to the inner ends of said hooks and extending down 25 within reach of the operator, whereby by pulling on either cord to throw its hook up into engagement with said head and then rocking

the lever the drum may be rotated in either direction, substantially as set forth.

5. The combination, with the casing having 30 an opening in its front to expose the name of the station, the drum within the casing provided with operating mechanism and with a polygonal hub or plate, of the head J , bearing against the rear face of the hub or plate and 35 provided with arms extending through the rear side of the casing at $a' a'$, bearings $j' j^2$ for said arms, and springs on the said arms pressing said head inward, substantially as set forth.

6. The combination, with the drum having a polygonal hub or plate E' , of the head J , having rearwardly-projecting arms, inner and outer brackets $j' j^2$, through which said rods pass, yokes $j^6 j^6$ within the said brackets and 45 apertured at their ends for the passage of the arms, the spiral springs pressing the rods inward, and the buffers $j^1 j^4$ on the outer ends of the rods between their collars j^5 and the end of the bracket j^2 , substantially as set forth.
